DOOR CHECK

James W. Holman, Tulsa, Okla.

Application August 24, 1945, Serial No. 612,369

2 Claims. (Cl. 16—63)

1

The invention relates to door checks and has for its object to provide a door check which may be used in connection with a door closer, and which door check comprises a cylinder having one of its ends anchored to the door frame, and its piston rod pivoted to a member carried by the door; the piston being provided with check valves and an adjustable ported regulating valve, through which regulating valve fluid passes to one side of the piston on the closing operation, and in the opposite direction simultaneously with the unseating of the check valve, upon opening of the door, following a rapid opening. Also to provide detent means in the connection between the piston rod and the door carried bracket for holding the door open position.

With the above and other objects in view the invention resides in the combination and arrangement of parts as hereinafter set forth, shown in the drawings, described and claimed, it being understood that changes in the precise embodiment of the invention may be made within the scope of what is claimed without departing from the spirit of the invention.

In the drawings:

Figure 1 is top plan view of the door check adapted for use in connection with a door closer, showing the same applied to a door frame and door.

Figure 2 is a front elevation of the device shown in Figure 1.

Figure 3 is an enlarged top plan view of the neck shown in Figure 1, showing parts in section to better illustrate the dent holding means.

Figure 4 is a vertical longitudinal sectional view through the check cylinder and piston, showing the parts in the position assumed when the door closing.

Figure 5 is a view similar to Figure 4 but showing the parts in the position assumed when the door is opening.

Figure 6 is a transverse sectional view through the ported regulating valve.

Figure 7 is a perspective view of a modified form of door check, showing the same practically concealed within the upper part of the door frame.

Figure 8 is a top plan view of the device shown in Figure 7.

Referring to the drawings, the numeral 1 designates a conventional form of door frame, 2 a door and 3 the door hinges. The door check comprises cylinder 21 pivotally connected at 22 to the door frame 1 and has reciprocally mounted therein a piston shaft 23. The piston shaft 23 terminates in a valve 24 which cooperates with a valve seat

2

25, and the valve is provided with longitudinally extending fluid ports 26, through which ports fluid passes during a door opening or closing operation. Shaft 23 is threaded at 27 into a reciprocating piston 28 having spring actuated check valves 29 therein, which check valves are closed on the door closing operation and during the checking operation, and at which time the oil or fluid passes through the ports 26, however, on the door opening operation the check valves 29 are opened for allowing a more rapid flow of fluid to the opposite side of the piston, thereby allowing the door to be quickly opened as shown in Figure 5. The valve seat 25 is carried by a sleeve 30, threaded into the piston, and the sleeve at opposite sides thereof is provided with ports 31. It will be seen that a simple door check is provided. Secured to the door 2, adjacent the hinging point 3, is a bracket 32 having an upstanding pin 33, the outer side of the pin being provided with a ball receiving recess 34, which recess receives the spring actuated detent ball 35 when the door is opened 90 degrees. The tension is sufficient to maintain the door in open position until overcome manually during a movement of the door. It will be seen by adjusting valve 24 in relation to valve seat 25, by means of the threaded connection 27 of the rod 23 in the piston 28, that the amount of fluid passing through the piston may be varied.

Referring to Figures 7 and 8, the door check in this form, has the internal parts of those shown in Figures 1 to 6, however the cylinder 21 is entirely concealed within the upper portion 36 of the door frame 1, and is hingedly connected at 37 thereto. The piston rod 23 is connected to a Z link 38 within the door frame, however the arm 39 of the Z link extends outwardly through a slot 40 in the side of the frame and is pivotally connected at 41 to an upstanding pin 42 carried by a bracket 43, secured to the upper end of the door 2, as shown in Figure 8. It will be seen that during a door closing or opening operation the device, particularly the cylinder, will be concealed from view at all times. By making the Z bar in this particular shape it is obvious that as the door opens the portion 38a will be moved outwardly and clear the ends of the slot 40 when the door is opened.

The invention having been set forth what is claimed as new and useful is:

1. A door check comprising a cylinder hingedly connected to a door frame, a reciprocating piston within said cylinder, a piston rod carried by said piston and having its outer end anchored to a hinged door, check valve means carried by the

piston and through which fluid within the cylinder passes to opposite sides of the piston, a constantly open port through the piston, said constantly open port being formed by a valve carried by the piston rod and cooperating with a valve seat and longitudinally extending ports carried by the valve end of the piston rod.

2. A device as set forth in claim 1 including adjusting means for the piston rod for varying the valve end thereof in relation to the valve seat, 10 carried by the piston rod.

JAMES W. HOLMAN.
